UNITED STATES PATENT OFFICE.

WOLCOTT A. HULL, OF NEW YORK, N. Y.

DESIGN FOR A LAMP-RESERVOIR.

SPECIFICATION forming part of Design No. 15,653, dated December 30, 1884.

Application filed May 16, 1884. Term of patent 7 years.

To all whom it may concern:

Be it known that I, WOLCOTT A. HULL, of New York, in the county of New York and State of New York, have invented a certain new and original Design for a Lamp-Fixture, of which the following is a specification.

This design relates to hanging lamps.

The accompanying illustration is a perspective view of a lamp-fixture embodying my design.

A designates the lamp-reservoir case. It is in the shape of an oblate spheroid and has a bright smooth surface.

B designates a shade-holder.

15 C designates arms extending from the lamp-reservoir case to the shade-holder. At the lower ends the arms C extend in ornamental scrolls c. Leaving the lamp-reservoir case A, they extend outward laterally, as at c', and 20 then extend upwardly in sinuous curves to the shade-holder B. At their junction with the shade-holder rosette-like ornaments c² are arranged. The upper ends of the arms con-

stitute hooks c³, resembling the hooks of a shepherd's crook.

What I claim as my design, and desire to secure by Letters Patent, is—

1. In a design for a lamp-fixture, the combination of a reservoir-case, A, of oblate spheroidal shape, and having a smooth bright surface, and arms extending upwardly therefrom, substantially as shown and described.

2. In a design for a lamp-fixture, a reservoir-case, A, arms C, having the ornamental scroll c, lateral extension c', rosette-like ornaments c², and hook-like portions c³, substantially as shown and described.

3. The design for a lamp-fixture, comprising a lamp-reservoir case, A, a shade-holder, B, and arms C, shaped and ornamented substantially as shown and described.

WOLCOTT A. HULL.
